UNITED STATES PATENT OFFICE.

JOSEPH H. ELLIOTT, OF ROCKFORD, ILLINOIS.

TOOTH-CROWN HOLDER.

1,278,124.

Specification of Letters Patent. Patented Sept. 10, 1918.

Application filed June 26, 1918. Serial No. 241,919.

To all whom it may concern:

Be it known that I, JOSEPH H. ELLIOTT, a citizen of the United States, residing at Rockford, in the county of Winnebago and State of Illinois, have invented certain new and useful Improvements in Tooth-Crown Holders, of which the following is a specification.

This invention relates in general to dentistry tools, and has more particular reference to means for holding a tooth crown while filing, grinding and polishing it.

Heretofore, various forms of tooth crown holders have been provided, all of which so far as I am aware, are either of such complicated construction as to render them impractical as a commercial product, or on the other hand, those of simpler construction are unsatisfactory and ineffective for general use as they are not applicable to all shapes and sizes of crowns and invariably distort the crowns when sufficient pressure is exerted to properly hold them.

The primary object of the present invention is to provide a tooth crown holder of generally improved construction and which overcomes the well recognized objections to those crown holders now in use. In other words, I have aimed to provide a crown holder adapted to firmly and securely hold crowns of all shapes and sizes and with a pressure corresponding with the work in hand and such as not to distort the crowns, and which is exceedingly simple in construction so that it may be manufactured at a low cost in proportion to the resultant advantages.

To this end, my invention in its preferred form comprehends a handle equipped with a sectional holding element or tine, the component members of which are adapted to be separated at various degrees, a single elastic tip supplied in various thicknesses, embracing both of said members and adapted when inserted in a crown to be expanded in substantially all directions by separation of the component holding members, and a simple means, such as an adjusting screw threadingly engaging one of the members and coöoperating with the other for separating the members to the proper degree and for holding them in separated relation.

Referring to the drawing,

Figures 1 and 2 are views of different

sides of a dental tool embodying my improvements;

Fig. 3, an enlarged sectional view illustrating the holding of a crown;

Fig. 4, a sectional view on the line 4—4 of Fig. 3; and

Fig. 5 shows three different sizes of tips, on an enlarged scale.

As will readily be seen from the drawing, my improved tooth crown holder is of exceedingly simple construction. It comprises in the preferred embodiment, a suitable handle 5, which carries the sectional holding member or tine, designated generally by the character 6. In the embodiment shown, this holding member is shaped to provide a shank 7 fixed to the handle and a cylindrical body 8 tapering toward its ends so as to provide a reduced holding end or tine 9 circumferentially serrated or grooved as at 11. The shank 7 is preferably formed with an elongated slot 12 and the body 8 is split longitudinally at 13 to form two component ends or members 14 which obviously are normally disposed in closely associated relation. By forming the shank 7 of proper resilient material, the end 14 may be sprung apart to the desired degree of separation. In order to regulate this separation to a fine degree and for holding the members 14 in such separated position, I have provided means in the form of an adjusting screw 15 threadingly engaged in one of the component members of the body 8 and bearing against the opposite member. It will be manifest that by turning the adjusting screw 15 inwardly, the members 14 will be separated, and reversing the movement, these members will spring back to their original position.

In the practice of dentistry, crowns of various thickness, shapes and sizes are required to be filled, ground and polished, and it is desired to firmly and securely hold these crowns without distorting them from their respective shapes, which in many instances have required much time and expert attention in forming. It is the purpose of this invention to sheath the members 14 with a single tip of elastic material, which entirely embraces the grooved periphery 11. These tips are made of various thicknesses and ordinarily three sizes, narrow, medium and thick are sufficient for the various requirements. A tip 16 fits snugly on the members

14 and is retained thereon by the peripheral serrations. By reason of the fact that this tip peripherally embraces both members 14, there is sufficient material in the tip so that 5 when the latter is inserted into a crown and the members 14 separated by turning the screw 15 the elastic materials will be separated laterally in substantially all directions and will thus conform to and be firmly 10 pressed into the irregular interior surface of the crown. By means of the screw 15, the pressure on the crown may be adjusted to a nicety and to such an extent without distorting the crown, that the crown will be 15 firmly and securely held and any operation may be performed thereon without danger of the crown loosening. When a smaller crown is to be held, a correspondingly smaller tip 17 is substituted for the tip 16, 20 and in like manner if the crown is of especially large size a larger tip 18 would be used. It will be especially noted that the proper tip is to be used on a given size crown so that when the members 14 are in 25 closed relation, the tip 16 will just fit inside the crown, and consequently, when the members 14 are separated, the best expanding and holding action is obtained.

It is believed that the foregoing conveys 30 a clear understanding of my improvements, and while I have illustrated the same in the preferred embodiment it should be understood that various changes might be made in the proportions and shapes of parts with-

out departing from the spirit and scope of 35 the invention as expressed in the appended claims:

I claim:

1. In a tooth crown holder, the combination of a sectional holding element having separable holding members, an elastic sheath embracing both members and adapted to be expanded by separation of said members, and means for moving the members to vary the degree of separation and 45 holding them in such position.

2. In a tooth crown holder, the combination of a handle, a sectional holding element fixed to the handle and comprising a pair of separable members normally disposed in close relation and having a constant tendency when separated to return to said normal relation, an elastic sheath embracing both of said members and adapted to be expanded by separation thereof, and 50 means on said holding element for moving the members to vary the degree of separation and for holding them in such position.

3. In a tooth crown holder, the combination of a pair of fingers, a single tip of elastic material embracing both of said fingers at one end, and an adjusting screw threadingly engaging one of the fingers and co-operating with the other for separating the finger ends and expanding the elastic tip 65 to the proper extent for holding a crown within which the tip has been inserted.

JOSEPH H. ELLIOTT.
